PRECIPITATION GAUGE

Norman R. Hastings, Huron, S. Dak.

Application May 8, 1956, Serial No. 41,395

Term of patent 14 years

(Cl. D52—1)

FIG. 2

FIG. 1

FIG. 3

Fig. 1 is an elevational view of a precipitation gauge, showing my new design;

Fig. 2, a top plan view; and

Fig. 3, a bottom view.

I claim:

The ornamental design for a precipitation gauge, as shown.
